UNITED STATES PATENT OFFICE

ABRAHAM NOVICK, OF FLUSHING, NEW YORK, ASSIGNOR TO F. L. SMITH'S MACHINE CO., INC., OF NEW YORK, N. Y., A CORPORATION OF NEW YORK

GUMMING DEVICE

Application filed November 10, 1927. Serial No. 232,273.

This invention relates to envelope-making machines, and has particular reference to gumming devices therefor.

An object of the invention is the provision of novel and improved means for protecting certain parts of the gum-applying mechanism from becoming coated with adhesive material when, in the operation of the machine, there occurs a failure to feed an envelope-blank through the gum-applying mechanism.

The gumming device of an envelope-making machine customarily operates continuously and in co-operation with the feeding mechanism and other portions of such machine. It is usual in this art to provide a gum applicator which contacts with the envelope-blank in the passage of the blank through the machine, thus transferring thereto gum or other adhesive which is supplied to the applicator from a suitable receptacle. This applicator is ordinarily in the form of a roller, between which and a co-operative pressure roller the envelope-blank is automatically fed. The envelope-blank feeding mechanism so co-operating with the gum-applying device that, under ordinary operating conditions, a blank is available for interposition between the applicator and the co-operating pressure roller at the time in the cycle of movement thereof when the gum-applying process is to be effected. It sometimes occurs, however, that because of temporary failure of the envelope-blank feeding mechanism to properly function, or because the supply of said blanks has become exhausted, no blank is available for interposition between the applicator and the pressure roller co-operating therewith. Under these conditions, and in the absence of means for preventing such an occurrence, the gum carried by the applicator is transferred therefrom to the pressure roller—the result being that a number of the blanks next passing through the machine will have gum applied to both their inner and outer surfaces, thereby not only spoiling such blanks but also interfering with the operation of the machine. The present invention embodies simple and efficient means for in-

suring against transfer of gum from the applicator to its co-acting pressure roller.

The invention will best be understood by reference to the accompanying drawings, wherein it is shown in its present preferred embodiment, and in which

Figure 1 is a transverse section of a portion of an envelope-making machine embodying a gum applicator and associated parts, certain of such parts being shown in elevation;

Figure 2 is a fragmentary detail illustrating certain of the parts shown in Figure 1, but with some of said parts in different operative positions;

Figure 3 is a fragmentary detail similar to Figure 2, but showing the parts in still other operative positions;

Figure 4 is a top plan view of the device embodying the invention, certain of the associated parts shown in Figures 1, 2, and 3 being omitted; and

Figure 5 is a section on line 5—5 of Figure 4, looking in the direction indicated by the arrows.

Like reference characters indicate like parts throughout the drawings.

Referring to the drawings: 1 and 1a of Figure 4 denote a framework, supported in which are a number of shafts, to be herein-after described. Referring to Figure 1, a gum receptacle 2 supplies gum or other adhesive material to a continuously-rotating doctor-roller 3, mounted upon a shaft 4. The doctor-roller contacts with and transfers gum to the periphery of the segmental portion 5a of an applicator 5. This periphery of the segmental portion 5a may be of oppositely-disposed helical conformation, or of such other configuration as to correspond to the shape of the area of the envelope-blank to which it is desired to apply gum. The applicator 5 is provided with a base 6, adapted to be attached to a hub 7, mounted on a continuously-rotating shaft 8. A stack of envelope-blanks (not shown) is adapted to be positioned on a feeding-table 9, and to be fed therefrom (by devices not shown) into the bight of feed rollers 10 and 13. Feed roller 10 is mounted on a shaft 11. Roller 13,

- which is mounted on shaft 14, is spring-pressed against roller 10, whereby said rollers co-operatively and frictionally forwardly feed an envelope-blank 12 (Figures 2 and 3).
- 5 After passing through the gumming device, the envelope-blank enters the bight of rollers 15 and 16, mounted respectively on shafts 17 and 18, by which latter rollers it is carried to other mechanism forming a part of the machine.
- A feeler 19 is mounted on a shaft 20, journaled in arms 21 and 21a, which arms are attached to a shaft 22, supported in frame 1-1a. The feeler is provided at its upper 15 end with a shoe portion, 23, constructed and arranged to frictionally contact with the envelope-blank 12 during the passage of the latter through the rollers 10 and 13, whereby said blank actuates said feeler to move it to 20 the right (as shown in Figures 1, 2 and 3). An adjustable stop 24 contacts with an adjusting arm 25, attached by a clamping-screw 26 to a shaft 22, whereby feeler 19 may be raised or lowered with reference to feed rollers 10 25 and 13 to bring it into proper operating position whereby it will be actuated by the frictional contact of its shoe portion 23 with the moving envelope-blank 12. A coil spring 27 maintains adjusting arm 25 in contact with 30 stop 24. Feeler 19 carries a pin 28, supporting one end of a link 29, the opposite end of which link carries a pin 30, extending through and movable in a slot 31 of an arm 32, attached by a clamping-screw 33 to a shaft 34.
- 35 Loosely mounted on shaft 34 is a shaft-rocking arm 35, through which pin 30 also passes. Attached to shaft 34 are roller-supporting arms 36 and 36a, journaled in which arms is pressure roller 37, adapted, when properly positioned, to press the envelope-blank 12 against the periphery of the segmental portion 5a of applicator 5, in order that gum may be transferred to said blank from said segmental portion.
- 40 Shaft 34 is journaled in two supporting arms 38 and 38a, which arms are mounted on a shaft 39, attached to which shaft, by any suitable means such as clamping-screw 40, is an arm 41, which, by the action of adjustable stop 42, may slightly rotate shaft 39 to bring pressure roller 37 into operating contact with the segmental portion 5a of applicator 5. A coil spring 43 maintains arm 41 in contact with adjustable stop 42. Arm 32 45 is provided with a lug 43a, carrying one end of a coil spring 44; and shaft-rocking arm 35 is provided with a similar lug 45, also carrying one end of a coil spring 46. The purpose of these springs will be hereinafter described.
- 50 Mounted on shaft 8, which carries applicator 5, is a cam 47 (Figures 1, 2 and 3), the purpose of which will be presently explained. The mode of operation of the device is as follows: Figure 1 illustrates the positions which the several parts of the protective mechanism occupy when the machine is in operation, but when no envelope-blanks are being fed through the gumming device. It will be noted from the dotted line 48 (Figure 1), which line indicates the path of travel 70 of the segmental portion 5a of applicator 5, that, in its rotation, said segmental portion does not contact with pressure roller 37, the reason therefor being that spring 46, acting through lug 45, shaft-rocker arm 35, shaft 34 75 and roller-supporting arms 36 and 36a, maintains said pressure roller 37 to the left and out of the path of travel of said segmental portion which carries the adhesive. However, when by reason of the frictional contact 80 of the feed rollers 10 and 13 with the envelope-blank 12, such blank is fed to the right (as shown in Figures 2 and 3), the friction of the blank with the shoe 23 of feeler 19 progressively moves said feeler, together with 85 the parts actuated thereby, into the position shown in Figure 2. It will be understood that the rotation of the applicator is timed (by gearing or other suitable means not shown) to synchronize with the movements 90 of the envelope-blank feeding mechanism. Thus, in its travel through rollers 10 and 13, the blank 12, by the action of feeler 19, pin 28, link 29, and pin 30, will have rotated shaft-rocker arm 35 upon shaft 34, to the 95 position shown in Figure 2, wherein it is about to be engaged by the nose portion of cam 47. Thus far pin 30 will merely have moved in slot 31, carrying with it shaft-rocker arm 35. Shaft 34 will not yet have been rocked, 100 so that arm 32, roller-supporting arms 36 and 36a, and pressure roller 37, journaled in said last-named arms, still remain in their original positions as shown in Figure 1. However, as soon as the nose of cam 47 contacts with the upper portion of shaft-rocker arm 35, pin 30 is carried to the extreme right-hand end of slot 31 in arm 32, and immediately thereafter the contact of said pin with the right-hand 105 end of the wall of said slot forces arm 32 into the position shown in Figure 3, producing a slight rotation of shaft 34, to which said arm is clamped. Roller-supporting arms 36 and 36a being attached to shaft 34, said arms are brought into a position where pressure roller 37 presses against the under surface of envelope-blank 12, forcing the upper surface thereof into contact with the segmental portion 5a of applicator 5, and resulting 110 in the transfer of gum from the applicator to the blank. So long as the dwell of cam 47 contacts with shaft-rocker arm 35, pressure will be maintained by roller 37 against the envelope-blank to which gum is being applied.
- 115 It will be noted from Figure 3 that when shaft-rocker arm 35 is under control of the dwell of the cam, feeler 19 is drawn to the right sufficiently to carry its shoe portion 23 out of contact with the blank 12, thereby 120 125 130

obviating the possibility of its scraping, scoring or tearing the blank. When, in the progress of the rotation of cam 47, its dwell passes out of contact with shaft-rocker arm 35, coil springs 44 and 46 restore the several parts to their original positions as shown in Figure 1.

The invention comprises simple, inexpensive, efficient and positively-acting means for insuring that gum shall be applied only to the desired portions of the envelope-blank.

10 I have described what I believe to be the best embodiment of my invention. I do not wish, however, to be confined to the embodiment shown, but what I desire to cover by Letters Patent is set forth in the appended claims.

I claim:

1. In an envelope-making machine, the combination with an applicator, means co-operative therewith for transferring gum to an envelope-blank and means yieldingly urging said applicator and co-operative means apart and normally holding them separated, of an actuator for said cooperative means moved to an operative position by movement of said blank, and means for acting on said actuator when it has been so moved, to move said co-operative means into pressure engagement with said applicator.

30 2. In envelope making, the combination of an envelope-blank, an applicator for carrying gum to be transferred to said blank, means for feeding said blank into juxtaposition with said applicator, and means actuated by frictional contact with said blank for effecting transfer of gum from said applicator to said blank.

35 3. In an envelope-making machine, the combination of means for feeding an envelope-blank, means for gumming said blank, and frictionally-controlled means actuated by movement of said blank for rendering said gumming means operative to gum the said blank.

40 4. In envelope making, the combination of means for feeding an envelope blank, means for supplying adhesive material, an applicator constructed and arranged to receive said adhesive material, and means actuated by frictional engagement with said blank for rendering said applicator operative to transfer such adhesive material to said blank.

45 5. In envelope making, the combination of means for feeding an envelope-blank, a gumming mechanism comprising cooperative members normally maintained in inoperative relation, and means actuated by frictional engagement with the blank for causing said members of the gumming mechanism to be brought into operative relation to apply gum to the blank.

60 6. In an envelope machine, in combination, a pair of elements adapted to form a blank engaging couple and including a gum ap-

plying element, means yieldingly urging said elements apart and normally maintaining them separated, means for relatively moving said elements to bring them together into cooperative relationship, said element moving means being normally inoperative, means operated by the work itself for shifting said element moving means to render the same operative, and means for operating the element moving means when said means is thus rendered operative.

70 7. In an envelope machine, in combination, a pair of elements adapted to form a blank engaging couple and including a gum applying element, means yieldingly urging said elements apart and normally maintaining them separated, a feeler movable by engagement with a blank but arranged to remain idle when no blank is being fed, means controlled by the feeler to effect approach of said elements when the feeler is moved, but to remain idle when the feeler remains idle, and power means operable on the feeler controlled means when the latter is moved by the feeler to press the elements together positively.

75 8. In an envelope machine, in combination, a pair of elements adapted to form a blank engaging couple and including a gum applying element, means yieldingly urging said elements apart and normally maintaining them separated, a feeler occupying a normal position from which it may be moved by a blank, and means normally inoperative but shifted to an operative position by movement of the feeler from such normal position to cause 100 said elements to be pressed together.

90 9. In an envelope machine, a pair of elements adapted to form a blank engaging couple and including a gum applying element, and means controlling approach and separation of said elements, comprising a control member movable by frictional engagement with a blank.

95 10. In an envelope machine, blank feeding means, a pair of elements adapted to form a blank engaging couple and including a gum applying element, means yieldingly urging said elements apart and normally maintaining them separated, mechanism for shifting one of said elements toward the other, an actuating member for said shifting mechanism, a continuously operating power member engageable with said actuating member to operate the latter, and means responsive to the feeding of a blank to move said actuating member into position to be engaged and operated by the power member when a blank is being fed.

11. In an envelope machine, blank feeding means, a pair of normally separated elements adapted to form a blank engaging couple and including a gum applying element, a power operated member, mechanism for shifting one of said elements toward the other, an actuating member therefor having provision 130

for limited lost motion relative to said mechanism between an inoperative position in which it escapes the power operated member, and an operative position in which it is engaged by the power operated member and moved thereby to actuate the shifting mechanism, and means controlled by the feeding of a blank to move said actuating member from its inoperative to its operative position in 10 which it will be engaged and moved by the power operated member.

In testimony whereof I have affixed my signature to this specification.

ABRAHAM NOVICK.
